UNITED STATES PATENT OFFICE.

PETER MANUEL WISE, OF NEW YORK, N. Y.

CONTINUOUS WRITING-TABLET.

No. 806,041.

Specification of Letters Patent.

Patented Nov. 28, 1905.

Application filed September 26, 1904. Serial No. 226,065.

To all whom it may concern:

Be it known that I, PETER MANUEL WISE, a citizen of the United States, residing at New York, in the county of New York and State 5 of New York, have invented certain new and useful Improvements in Continuous Writing-Tablets; and I do hereby declare the following to be a full, clear, and exact description of the invention, such as will enable others 10 skilled in the art to which it appertains to make and use the same.

This invention relates to certain new and useful improvements in mechanisms for feeding a sheet or strip of material automatically 15 upon a writing-surface.

The object of the invention is to construct a simple automatic sheet-feeding mechanism which is efficient in operation, as well as durable in construction. Said mechanism may 20 be attached to any existing writing-surface, such as a desk or battery-box, to permit of the paper to be fed thereupon.

Another object of the invention is to improve the construction of a device which is 25 adapted to automatically feed a sheet of paper upon a hard surface.

A still further object of the invention is to construct a spring-actuated mechanism, which is manually controlled, for the purpose of supplying a sheet of material continuously upon a suitable writing-surface.

With these and other objects in view the invention consists in certain novel constructions, combinations, and arrangements of parts, as 35 will be hereinafter fully described, illustrated in the accompanying drawings, and more particularly pointed out in the claims hereto appended.

In the drawings, Figure 1 is a view in side 40 elevation of a mechanism constructed in accordance with the present invention. Fig. 2 is an elevated fragmentary front view of the mechanism depicted in Fig. 1.

In carrying out the present invention I have 45 constructed a mechanism which is adapted for the purpose of feeding paper more particularly to the small desk over the battery-box of the usual telephone outfit; but this invention is applicable to any desk, counter, or any 50 place where paper is used for memoranda. This mechanism is also adapted to be employed as a toilet-paper holder.

Referring to the drawings, 1 designates a 55 casing which comprises in its construction parallel side plates 2 and 3. The side plates 2 and 3 form a compartment 4, within which is

mounted the gearing mechanism for controlling movement of rolls 5, 6, and 7, which are mounted on the inner vertical plates 3 of the casing 1.

The gearing or spring-motor mechanism comprises in its construction a shaft 8, which is journaled in plates 2 and 3. Mounted upon shaft 8 is a gear-wheel 9, to which is secured at one of its ends a power-spring 10. The opposite end of the power-spring 10 is secured to shaft 8. An inclosing housing 11 is secured to gear-wheel 9 for the purpose of forming a protecting-casing for spring 10. A shaft 12, upon which is mounted roll 6, is journaled 70 in the parallel plates 2 and 3 above shaft 8 and is provided with a pinion 13, which meshes with cog-wheel 9. A cam 14 is keyed upon shaft 12 adjacent to plate 3 within the compartment 4. A release-key or dog 15 is journaled upon plate 3 within the compartment 4 and is normally held in engagement with cam 14 by means of a spring 16, which is secured at 75 17 to plate 3 within the compartment 4. The spring 16 normally engages the upper edge of member 15. The pawl 15 is provided with a toothed or hooked end 18, which is adapted to engage the stop formed upon cam 14 for the prevention of rotary movement thereof.

A large paper-roll 5 is journaled upon the 85 lowest portion of plates 3 of the casing at 19. The paper-roll 5 is detachably mounted upon the casing 1, thereby permitting of the insertion of a new roll when the supply of paper has been consumed upon that which is in position upon the casing 1. The rubber-coated feed-roll 6 is mounted upon the paper-roll 5, but is not normally in engagement with the same. A notch 20 is formed upon the upper edge of each plate 3, providing sockets or receiving means for the spindles 21 of the auxiliary feed-roll 7. The roll 7 is detachably mounted upon the casing within the sockets 20. The roll 7 is in frictional engagement with roll 6.

The plates 2 and 3 are provided with right-angled integral extensions or flanges 22, which are adapted to be secured to the supporting-surface of a desk, battery-box, table, or any similar object upon which it is desired to feed the paper from roll 5.

A cover, which is shown by dotted lines 24, is adapted to be positioned on the casing 1 for entirely closing the rolls of the gearing mechanism. If the cover is positioned upon the 110 casing 1, it will be necessary to provide suitable apertures through which the sheet of

material which is passed between the rolls 6 and 7 is adapted to be discharged. An aperture also must be formed upon the cover, through which the outer projection of the releasing-key 15 will be permitted to project, so that the operation of the driving mechanism may be controlled from the outside of the casing 1.

When the mechanism is in the position shown in Fig. 1, the same is locked against movement. If it is desired to discharge the sheet from the roll 5 between rolls 6 and 7 and upon the writing-surface, it will be necessary to cause movement of the finger-engaging portion 25, which is threaded at 26 upon the pawl 15, thereby moving said pawl or member 15 upon its pivot, raising the hooked end 18 from engagement with cam 14, permitting of the potential energy stored in the power-spring to be exerted upon the gear-wheel 9, consequently causing rotary movement of pinion 13, which is keyed to shaft 12. When rotary movement is imparted to shaft 12, similar movement is also imparted to rolls 6 and 7, respectively. If a sheet of paper is supplied to rolls 6 and 7 and fed between the same, the roll 7, which is in frictional contact with the roll 6, will cause the paper to be fed onto the writing-surface as movement is imparted to shaft 12. As soon as a sufficient amount of paper has been fed through the rolls 6 and 7 upon a writing-surface or the like to lock the mechanism it will be necessary to release pawl 15, the hooked end 18 of which will be caused to move into engagement with cam member 14 and to positively lock shaft 12 against rotary movement as soon as the hooked end 18 comes in contact with the shouldered or projecting portion of cam 14. The locking of the shaft 12 against rotary movement also prevents similar movement of gear-wheel 9, and consequently prevents the exertion of the power-spring to cause movement of the rolls.

When it is desired to wind the spring, it will be necessary to apply at the squared portion 27 of shaft 8 a key or the like for imparting rotary movement to the shaft 8. Keyed upon an extension of shaft 8 and between the plate 3 and the paper-roll 5 is a pinion 28, which is normally engaged by the pawl 29. The pawl 29 is pivotally mounted upon the plate 3. Owing to the construction of the pinion 28 and pawl 29, rotary movement is only imparted to shaft 8 in one direction, such movement being manually imparted to shaft 8 by a key or the like.

While I have described in the foregoing description and depicted in the accompanying drawings the preferred construction of my invention, it will be obvious to one versed in the art to which this invention relates that certain alterations, modifications, and changes may be made, and I therefore reserve the right to make such alterations, modifications,

and changes as shall fairly fall within the spirit and scope of the present invention.

Having thus fully described my invention, what I claim as new, and desire to secure by Letters Patent, is—

1. In a device of the character described, the combination with a casing, of a sheet-supplying roll carried thereby, a plurality of rolls journaled upon said casing above said supplying-roll, a gearing mechanism carried by said casing, comprising a shaft, a gear-wheel loosely mounted upon said shaft, a coiled spring secured to said shaft at one end and to said gear-wheel at the opposite end, an extension projecting from one of said rolls above the supplying-roll, a pinion secured to said extension and meshing with said gear-wheel, means for winding said coiled spring and retaining the same in a locked position, a cam provided with a shouldered portion keyed to the extension of said roll, a release-key pivotally mounted upon said casing and normally in engagement with said cam, and means for normally retaining said key in locking engagement with said cam.

2. In a device of the character described, the combination with a casing, of a supply-roll journaled in said casing, a pair of rolls positioned above said supply-roll, a spring-motor secured to said casing and connected in an operative position with one of said pair of rolls, said spring-motor capable of causing continuous rotary movement of said pair of rolls for feeding a sheet from said supply-roll therebetween, eccentric means connected with one of said pair of rolls and coacting with said motor, and a manually-operated locking member secured upon said casing and normally in engagement with said eccentric means capable of securing the same in a fixed position.

3. The combination with a casing, a partition formed within said casing near one end thereof, said partition providing a compartment within said casing, a supply-roll secured within said casing, feeding-rolls positioned within said casing, a driving mechanism for said feeding-rolls mounted within the compartment of said casing, said driving mechanism comprising a shaft, a gear-wheel loosely mounted upon said shaft, a spring secured to said shaft and wheel, pawl-and-ratchet means carried by said casing and coacting with said shaft for normally preventing movement thereof in one direction, and manually-controlled locking means positioned within said compartment and coacting with said driving mechanism for controlling movement of said feeding-rolls.

4. In a mechanism of the class described, the combination with a casing, of a supply-roll journaled in said casing, a partition secured in one end of said casing, a pair of feeding-rolls journaled in said casing contiguous to said supply-roll, a driving mechanism for said feed-

ing-rolls mounted within said casing between one end thereof and the partition, said driving mechanism comprising a shaft, a gear-wheel mounted upon said shaft, a spring secured to 5 said wheel and shaft, means for retaining said shaft in a fixed position, a pinion secured to one of said feeding-rolls and meshing with said gear-wheel, a cam connected to said feeding-rolls and pinion, and manually-operated 10 means engaging said cam for normally preventing movement of the same.

5. A device of the character described, comprising a casing, feeding-rolls journaled in said casing, a driving mechanism for said feeding-rolls, comprising a shaft, a pinion secured to said shaft, a pawl secured to said casing and normally engaging said pinion, a gear-wheel mounted upon said shaft, a coiled spring secured to said shaft near one end and to the 15 gear-wheel near its opposite end, a pinion coacting with said feeding-rolls and meshing with said gear-wheel, eccentric means connected to said pinion, a release-key carried by said casing normally engaging said eccentric 20 means for preventing movement of the same.

6. A device of the character described, comprising a support, a feeding mechanism carried by said support, a driving means for said feeding mechanism, said driving mechanism 25

comprising a shaft journaled in said support, 30 a pinion secured to said shaft, a pawl carried by said support and normally engaging said pinion, a gear-wheel loosely mounted upon said shaft, a spring secured to said shaft and wheel, a pinion mounted upon said support 35 and coacting with said feeding mechanism, said pinion meshing with the gear-wheel, a cam connected to said pinion, and locking means carried by said support and engaging said cam. 40

7. A device of the character described, comprising a support, a feeding mechanism carried by said support, a driving mechanism positioned upon one side of said support, said driving mechanism comprising a shaft, a wheel 45 loosely mounted upon said shaft, a coil-spring secured to said shaft and wheel, a pinion carried by said shaft, a pawl carried by said support and engaging said pinion, connecting means for said feeding mechanism and wheel, 50 and locking means coacting with said connecting means.

In testimony whereof I hereunto affix my signature in presence of two witnesses.

PETER MANUEL WISE.
